AIRPLANE CARBURETOR

Milton J. Kittler, Detroit, Mich., assignor, by
mesne assignments, to Chandler-Evans Corpora-
tion, Meriden, Conn., a corporation of Dela-
ware

Application October 28, 1936, Serial No. 107,961
Renewed June 2, 1939

3 Claims. (Cl. 261—34)

The object of this invention is to eliminate one of the hazards of flying. In the carburetor described herein an automatic fuel pump operated by the vacuum below the throttle delivers extra fuel every time the throttle is opened and substantially atmospheric pressure is restored below the throttle. If landing with the throttle partly closed, the engine ignition is switched off, the vacuum is destroyed below the throttle and this destruction of the vacuum causes the diaphragm of the pump to function and fuel is ejected into the mixture chamber and drawn into the hot cylinders before the engine has ceased to rotate. If one of the engines should have a hot spark plug, ignition might take place at very low engine speed with the result that owing to the high compressions used a very violent shock would be transmitted to the engine and to the propeller. Alternatively the engine might start up and move the plane forward or cause the plane to deviate from its path, if there were more than one engine. It is therefore highly desirable that before switching off there should be some means of rendering the accelerating fuel pump temporarily inoperative. In this type of carburetor means are provided for reducing the mixture strength at extreme altitudes, preferably by transmitting the effect of the low pressure effective at the engine or motor side of the throttle of the carburetor to the fuel supply means to reduce the pressure on the fuel being supplied thereby to lean the mixture. I have discovered that if before switching off the ignition the mixture or altitude fuel control valve is thrown to the extreme lean position and if means are arranged so that by so doing the accelerating pump is put out of commission (and of course the accelerating fuel pump is of no value at ceiling altitudes), the above mentioned difficulty is avoided. When switching off, the engine will quit with a lean mixture and what is more important, and the gist of the invention involved here, a mechanical "hookup" is provided whereby the fuel pump is put out of commission when the mixture or altitude fuel control valve is put into the lean position by sealing up the vacuum chamber which operates the diaphragm of the accelerating pump. Then the above mentioned hazards are completely eliminated.

Figure 1 shows the carburetor to which this invention is applied, together with the accelerating pump and is a cross sectional elevation taken on the plane of the principal fuel passage.

Figure 2 shows the corresponding drawing

taken on the plane parallel to that of Figure 1 through the means for putting the accelerating pump out of action at landing.

Fig. 3 is a plan view of Fig. 1 with parts broken away and parts in section showing certain features of the invention.

The carburetor chosen for illustration of the invention is of the variable Venturi type in which the throttles serve both as throttles and as walls defining the venturi. In this carburetor, fuel is supplied from a fuel pump and enters the carburetor at A and passes through passages to orifices controlled by needle valves C—C into a constant pressure fuel chamber T. The pressure in the chamber T is maintained constant by mechanism including levers B pivoted at P and suitably connected with flexible diaphragms J and K as more particularly disclosed in my co-pending application Serial No. 107,386 filed October 24, 1936 and in Patent 2,088,464 dated July 27, 1937. The flexible diaphragms J and K constitute the opposite side walls of the constant pressure fuel supply chamber T and each of them forms one wall of one of a pair of air chambers L and M which communicate with each other through a passage D and with the carburetor air entrance S through a pipe N. Restriction N' restricts the air flow through the pipe N and serves to modify the effects of depression created in the pipe F', passage D which communicates with pipe F'', and a pipe F''' which communicates with the throat of the venturi, by virtue of the low pressure or suction created in the throat of the venturi. The venturi is formed by throttles 30 and 31 which are rotatable between open and closed positions, the throttles being shown in closed position in Figs. 1 and 2. The flow of air through pipes F' and F'' is regulated by the valve F and lever 21. A nozzle bar H provides the main fuel orifices or jets and is disposed between the two throttles 30 and 31.

The fuel from the constant pressure supply chamber T flows through a restriction R, the opening in which is controlled by a needle which is moved toward or from a position closing the orifice R by mechanism including a double thrust collar 12 which is engaged by a lever 13 pivoted at 28, which lever carries a cam follower 14 at all times engaged in a cam track formed in a cam track member 15. The cam track member 15 is carried by a pivoted shaft 16 which also carries a gear 18 which meshes with a gear 20 in turn meshed with a gear 19. As the gear 20 is secured to a stub shaft on the throttle member 30 and as the gear 19 is simi-

larly secured to a stub shaft on the throttle member 31, rotary movement of the shaft 16 will open or close the throttle members 30 and 31 and simultaneously open or close the orifice R. As the 5 throttles are progressively opened the needle valve 10 progressively opens the orifice R to admit the progressively increased flow of fuel to the nozzles in the nozzle bar H.

Reference will now be made to that portion 10 of the device to which this invention is more particularly directed, that is, the accelerating fuel pump and associated mechanisms. A cavity or chamber in the carburetor body is divided into an accelerating fuel chamber 54 and a pressure chamber 58 by means of a diaphragm 55. The accelerating fuel pump chamber 54 is connected with the constant pressure fuel chamber T by a passage controlled by a valve 53. The diaphragm 55 is normally urged toward the left (Fig. 2) by 15 springs 52 while a reduction of pressure in chamber 58 tends to move diaphragm 55 to the right (Figs. 1 and 2). Chamber 58 (Figs. 2 and 3) communicates through passages 80—81 with the inside of the hollow throttle 31, the down stream 20 face of which is of Venturi form and communicates through a series of openings 59 with the mixture outlet O which leads to the engine. A valve 82 is mounted on the end of a shaft 83 in turn mounted in a sleeve guide 84 secured within 25 the body of the carburetor. An extension 85 from the lever 27 is arranged to engage with the end of shaft 83 when the lever is moved to the left or counterclockwise (Fig. 3) into a position which opens valve F the arrangement being such 30 that when the valve F is opened the valve 82 is closed against its seat. A spring 86 tends to open the valve 82 when the extension 85 is disengaged from the end of the shaft 83, that is, when the lever 27 is moved to the right or clockwise 35 (Fig. 3). A take-up spring 87 permits a limited movement of lever 27 after the valve 82 has been seated. A spring loaded valve 57 normally closes an outlet orifice from a passage 40 leading from accelerating fuel chamber 54 to the space above the throttles 30—31 so that under 45 certain conditions additional fuel may be supplied to the engine.

The automatic pump constituted by the diaphragm 55 and its related mechanisms normally 50 discharges fuel past the valve 57 every time the throttle is opened and the pressure in the mixture outlet O increases since such increased pressure effect is transmitted into the chamber 58 thereby to permit the springs 52 to 55 move the diaphragm 55 to the left. Alternative means or supplemental means are provided for closing the valve 82 when the throttles are closed. It will be observed from Figs. 1 and 2 that a lever 88 is mounted on a fulcrum 89 and has 60 its lower end arranged in the path of a projection 90 carried by the throttle 31. The upper end of lever 88 is forked as at 88' so as to straddle that portion of the head of shaft 83 carrying valve 82 which is engaged by the member 85 but, 65 nevertheless, is arranged to engage with the shaft operating mechanism so that when the throttles are closed the engagement of projection 90 with lever 88 will effect closing of the valve 82.

Operation

When landing and immediately before turning 70 off the ignition, the valve F is moved to the extreme counterclockwise position that is to say, the valve F is opened wide. This operation closes the valve 82 thereby sealing off chamber 58 so

as to maintain the low pressure therein and to hold the diaphragm 55 as far to the right (or against moving to the left) as its position then is. This prevents the springs from moving the diaphragm to the left (Fig. 2) so that no fuel 5 from chamber 54 will be ejected past valve 57. If this safety device were not provided then if the engine were shut off (especially with the throttle partly closed) the low pressure in chamber 58 would be broken at about the time the 10 engine was coming to a stop, but before the engine actually had stopped. Under such circumstances of ordinary conditions the diaphragm 55 would be moved to the left and the fuel in chamber 54 would be suddenly discharged 15 through the outlet nozzle 51, and, if there were sufficient heat in any engine cylinder to cause ignition of the fuel thus supplied, a very dangerous result could obtain. Such possibilities are entirely obviated by the invention. 20

The fact that the engine is stopped under the extreme lean condition is an additional safety device because it causes the mixture in the cylinder after the engine is switched off to be less liable to explode than if the normal mixture 25 were present and therefore the engine will stop promptly with the turning off of the ignition, which is the object of this invention.

Alternatively, even if the operator forgets to put the lever 27 into the lean position provided he 30 closes the throttle 31, the valve 82 will still be shut off and the engine will quit promptly immediately the ignition is switched off.

In the event that the pilot changes his mind and decides not to make a landing, he immediately throws the valve 27 into the rich position for low altitude, that is to say, he closes the valve F and at the same time he opens the throttles 31 and 32. The result of these maneuvers is to admit atmospheric air past the throttle 40 through the opening 59, along the passage 81, past the valve 82, down the passage 80, into the chamber 58, re-establishing atmospheric pressure in this chamber. The springs 52 and diaphragm 55 then move to the left and eject fuel 45 through the nozzle 57 in Fig. 1 into the air entrance of the carburetor. In the event that the pilot changes his mind and wishes to re-ascend and make a second attempt to land, it is of the utmost importance that the engine shall pick up 50 without any hesitation.

What I claim is:

1. In a carburetor having an air entrance, a throttle valve, and a mixture outlet, fuel supply means for said carburetor, a spring operated accelerating fuel pump including a displacement member and a fuel chamber into which said displacement member may be moved by action of the spring, a fuel passage connecting said fuel supply means with said fuel chamber, a non-return valve in said fuel passage for admitting fuel to said fuel chamber, a fuel outlet leading from said pump, a variable pressure chamber into which said displacement member may be drawn for operating said pump on its suction stroke, a passage connecting said variable pressure chamber with said mixture outlet, a valve in the second said passage, means for closing the last said valve, a mixture control valve for altitude effective to vary the flow through said 70 fuel supply means, and means interconnecting said mixture control valve with said valve closing means whereby as the altitude control is moved to the high altitude position the valve in the second said passage is closed. 75

2. In a carburetor having an air entrance, a throttle valve and a mixture outlet, fuel supply means for said carburetor, a differential pressure operated accelerating fuel pump, a fuel passage connecting said fuel supply means with said pump, a non-return valve in said fuel passage, a fuel outlet leading from said pump, means for operating said fuel pump including a passage connected with said mixture outlet for subject-
5 connecting the pump to pressure variations in said mixture outlet, a valve in the second said passage, manual means for closing the last said valve, a mixture control valve for altitude effective to vary the fuel flow through said supply means,
10 said mixture control valve being interconnected with said manual means and the throttle valve being also interconnected with said manual means whereby when the throttle valve is closed and also when the altitude control is moved to
15 20 the high altitude position the first said valve is closed.

3. In a carburetor having an air entrance, a throttle valve and a mixture outlet, a primary fuel supply chamber, a flexible diaphragm forming one wall of said primary chamber, said chamber having a connection with a source of fuel
25

and being adapted to receive fuel at one side of said diaphragm, means providing an air chamber at the other side of said diaphragm, a passage connecting said air chamber with the air entrance of said carburetor, a second passage connecting said air chamber with the mixture outlet, a valve in the second passage, a secondary fuel supply chamber having a flexible diaphragm forming one wall thereof, means for delivering fuel from said secondary fuel chamber to said mixture outlet, a secondary chamber located at the other side of said second diaphragm, as respects said secondary fuel chamber, said second air chamber having a connection with the mixture outlet, a valve controlling the connection between said second air chamber and said mixture outlet, a fuel passage connecting the two fuel supply chambers, a check valve in said connecting fuel passage, a fuel discharger nozzle, a valve for controlling air flow through said connection between said second air chamber and said mixture outlet, and means adapted to close said air flow control valve and to open the valve controlling said passage connecting the first mentioned air chamber and the mixture outlet. 20 25
